UNITED STATES PATENT OFFICE.

CHARLES ATWOOD WILSON, OF WEST PERU, MAINE, ASSIGNOR TO HORACE E. BOWDITCH
AND JAMES R. TOWNSEND, BOTH OF AUGUSTA, MAINE.

CRATE OR BASKET.

1,161,755.

Specification of Letters Patent. Patented Nov. 23, 1915.

Application filed August 22, 1914, Serial No. 857,986. Renewed October 18, 1915. Serial No. 56,591.

To all whom it may concern:

Be it known that I, CHARLES ATWOOD WILSON, of West Peru, in the county of Oxford and State of Maine, have invented certain new and useful Improvements in Crates or Baskets, of which the following is a specification.

My invention relates to crates or baskets made from dowels and secured together by wires and the object of the invention is to make a basket of this type which can be made at low cost and of great strength.

The invention consists of a crate or basket constructed and put together as hereinafter described and claimed.

My invention may best be understood by reference to the accompanying drawing in which is shown one form of basket constructed according to my invention.

20 In the drawing, Figure 1 is a side elevation of my basket with certain portions cut away and other portions in section, Fig. 2 is a plan, and Fig. 3 is a detail showing the manner of attaching side handles when two handles are to be used.

The basket is made up of a series of upright dowels *a* which are arranged to form the four sides, the baskets formed according to my invention being generally rectangular 30 in shape.

The dowels *a* are by preference inclined outwardly so that the top will be somewhat larger than the bottom.

The upper ends of the upright dowels *a* 35 are connected together by a flexible binder which is preferably a piece of steel wire *c*, the wire passing through holes in the dowels and through holes formed in the spacing blocks *b* which are as here shown, short dowel sections of the same diameter as the main dowels. The wire extends entirely around the upper rim of the basket and the ends are brought together and twisted as at *c'*.

45 The bottom of the basket is made up of a series of dowels *d* laid horizontally with their ends interposed between two opposite sections of the side dowels. If the basket is to be square one fourth of the upright 50 dowels will engage the horizontal dowels at each end of the bottom section. The other two portions containing one fourth each will lie outside of the end bottom dowels and be substantially parallel therewith.

55 The bottom of the basket is secured by

threading the binding wire *c* through the lower ends of the two opposite upright sections, the corresponding ends of the bottom dowels and through the lower ends of the remaining uprights and spacing blocks *b'* 60 which are inserted to properly space them from one corner to the next. Thus two sides of the bottom are formed by interlocking the upright with the bottom dowels and the other two sides are formed by the wire, the 65 spacing blocks and the lower ends of the upright dowels. The strength and stability of that portion of the basket is dependent mostly on the strength and stiffness of the wire and in making these baskets I use wire 70 which is relatively stiff and strong.

Handles are provided according to the size of the basket and the use to which it is to be put.

In Fig. 1 I show a bail handle composed 75 of a wire bail *e* engaging a wire loop *f* which is bent over the upper binding wire *c* on each side of the central upright dowel.

In Fig. 3 I show a side handle suitable for use in bushel baskets, clothes baskets, 80 etc. In this instance two of the upright dowels are extended upward a considerable distance above the upper edge of the basket and are there joined by a cylindrical handle *g*. A wire *g'* extends through the upper 85 ends of the dowels and through the handle.

Baskets of various sizes and shapes may be made on this principle. They are strong, durable and may be cheaply made. One great advantage of them for farm work is 90 that being open, they allow all dirt, rocks, etc., to sift down through and escape so that it is not carried into the barn or cellar. This is particularly important in handling and storing potatoes.

95

I claim;—

1. A crate or basket consisting of a series of upright dowels forming the sides of said basket, a series of horizontally disposed bottom dowels having their ends interposed between the lower ends of two opposite portions of said upright dowels forming the bottom of the basket, perforated spacing blocks interposed between the upper ends of the upright dowels and between the lower 100 ends of the upright dowels not engaged by the bottom dowels, an upper flexible binder threaded through said blocks and the upper ends of the upright dowels and a lower flexible binder threaded through the ends of 105 110 115

said horizontal dowels and the lower ends of said upright dowels and their spacing blocks.

2. A crate or basket consisting of a series of upright dowels forming the sides of said basket, a series of horizontally disposed bottom dowels having their ends interposed between the lower ends of two opposite portions of said upright dowels forming the bottom of the basket, perforated spacing blocks interposed between the upper ends of

the upright dowels, a flexible binder threaded through the upper ends of the upright dowels and their spacing blocks and means for securing the bottom dowels to the upright dowels.

In testimony whereof I have affixed my signature, in presence of two witnesses.

CHAS. ATWOOD WILSON.
